UNITED STATES PATENT OFFICE.

ONESIME HEBERT, OF MONTREAL, QUEBEC, CANADA, ASSIGNOR TO UNIVERSAL CAR & HOSE COUPLER COMPANY, OF OKLAHOMA, OKLAHOMA.

CAR AND TRAIN-PIPE COUPLING.

1,363,973.

Specification of Letters Patent. Patented Dec. 28, 1920.

Application filed September 1, 1916. Serial No. 118,103.

To all whom it may concern:

Be it known that I, ONESIME HEBERT, a subject of the King of Great Britain, residing at Ville St. Laurent, Montreal, in the Province of Quebec, Dominion of Canada, have invented new and useful Improvements in Car and Train-Pipe Couplings, of which the following is a specification.

The invention to be hereinafter described relates to car and train pipe couplers.

In order to more clearly disclose the construction, operation, and use of the invention, reference should be had to the accompanying drawings forming part of the present application. Throughout the several figures of the drawings like reference characters designate the same parts.

In the drawings:—

Figure 1, is a top plan view of a pair of the couplers, interlocked,

Fig. 2, is a side view of Fig. 1,

Fig. 3, is a side elevation of one coupler;

Fig. 4 is an opposite side view of the same coupler,

Fig. 5, is a vertical cross section on line 5—5 of Fig. 6.

Fig. 6, is a horizontal cross section on line 6—6 of Fig. 5;

Fig. 7, is a rear end view of a coupler head with draw bar removed;

Fig. 8, is a front end view of the same; and

Fig. 9, is a view similar to Fig. 1, showing a Janney coupler.

The main object of the invention is to provide a powerful, perfectly flexible coupling which will automatically adapt itself to all degrees of curvature in the track and all differences of level between cars, giving perfect coupling and uncoupling action in all positions. A further important object is to provide a coupling which will effect simultaneously with the coupling of the cars, an accurate automatic coupling of all train pipes, avoiding the necessity of going between the cars.

Referring to the drawings in detail, 1 indicates a hollow coupling head or shell adapted to carry one set of coupling elements and to receive the other or coöperating set of

coupling elements carried by another head, as will later appear. Consequently, each head has its forward end open for about one-half of its width and is chambered out to about one half of its length, as will be clear

on reference to Figs. 6 and 8. The inside

walls of each head carry two fixed coupling hooks 2 extending forwardly beyond the head for a distance approximately equal to the length of the chamber. One hook is at the top and one at the bottom of the head, 60 with a space between, the space being about equal to the thickness of one of the first hooks. The forward end of each hook is rounded to guide it to position in the chamber of the coöperating head as the couplings 65 are interlocked. To similarly guide them vertically, the hooks are beveled vertically as at 3. As shown in the drawings the hooks 2 are integral with the heads. Preferably they will be cast integrally and at one operation with the head. Between the two fixed hooks is pivotally mounted the horizontally swinging knuckle 4 formed with a hook 5, interlocking shoulder 6, rearward ear 7, and trip or release toe 8. The knuckle 4 is 70 mounted to swing horizontally about a vertical pivot rod 9 passed through a vertical bore in the ear 7 and similar bores in similar ears 10 on the outer face of the head. To enable the pivoting of knuckle 4, the wall of 75 the head is provided with a rectangular opening 11 between the ears 10 thereon. Through this opening is passed the ear 7, the pin 9 being slipped into place to secure it. One very important point of this arrangement is the two point lock for each knuckle, or four point lock for each pair of interlocked heads, as will be clear on reference to 80 Fig. 6. As shown in said figure the knuckle 4 is interlocked with the head to which it is 85 pivoted by means of an ear 7 entering the opening 11 and also with the mating coupler head by means of the shoulder 6 engaging one side of the opening 100 in said mating head. In order to maintain the knuckle 4 90 normally in operative position, a small spring actuated plunger 12 is used. It is simply a small rod slidably seated in a small bore in the rear face of the knuckle and having a rounded end at all times in sliding engagement with the inner rear wall of the head. A coil spring 13 in the bore and compressed by plunger 12, serves to maintain the 95 knuckle in its operative position.

The rear end of each head is considerably 100 thickened and provided with a vertical passage extending from top to bottom and increasing in width from front to rear, as at 14. Within this passage and extending through the top and bottom walls of the head 110

is the coupler pin 15. Its lower end projects slightly below the bottom of the head, as shown. On this pin is horizontally pivoted the inner end member 16 of a vertically flexible draw bar. The upper edge of this member, to the rear of pin 15, is triangular or wedge shaped in lateral vertical cross section, as at 17, and co-operates with two oppositely inclined surfaces 18 forming a groove or channel in the rear part of the inner face of the top of the head—see Figs. 2 and 5. On reference to Fig. 5, it will be noticed that the vertical thickness of the member 16 is considerably less than the distance between the inner faces of the top and bottom walls of the head, allowing considerable vertical movement between the member 16 and its head. This overcomes the differences between loaded and empty cars, in their heights above the rails. The swing of the head about the vertical pivot pin 15 avoids binding and maintains perfect coupling on any and all curves. But, its principal function is to permit the act of coupling on very sharp curves, which is not possible with the present couplers. When coupling on a very sharp curve, the rounded ends of the fixed hooks 2 engage the inner edge of the side wall of the cooperating head and the two heads are swung on their pivot pins 15 and accurately aligned as they interlock. As soon as they are disengaged and separated, the weight of each head immediately aligns it with the draw-bar, 35 through the action of the wedge 17 and incline planes 18, as will be obvious. The draw bars, as in other couplings, are always aligned with the longitudinal center of the car. Therefore, the coupling heads are always in position for coupling.

To the inner end member 16, of its draw bar, is flexibly connected the outer or rear member 19 having a forked end 20, through the branches of which is passed a horizontal draw-bar pin 21. The member 16 extends between the branches 20 and pivots vertically, about pin 21. It carries an extension 22 projecting rearwardly from its lower face and corresponding to a forwardly directed extension 23 of the upper face of the rear member 19 between the branches of the forked end 20. These two extensions form, practically, a cylindrical chamber within which is housed a stiff coil spring 24'. This spring acts to keep the two sections of the draw bar aligned, normally, and is sufficiently strong to overcome the weight of head 1 and the parts carried thereby. In case of excessive vertical difference between the coupled cars, in heights above rails, the draw bar will flex about pivot pin 21, compressing spring 24' and automatically adjusting itself to this difference. Thus, the coupling head and its operative parts will automatically return to normal position immediately upon

uncoupling. To effect uncoupling it is only necessary to force either of the shoulders 6 to inoperative position. As either of the knuckles 4 is thus swung, the innermost end of its hook will engage the toe 8 of the 70 knuckle of the interlocked head causing that knuckle, also, to swing on its pivot and withdraw its shoulder to inoperative position, thus simultaneously disengaging the two knuckles and uncoupling the two heads. 75 To effect this movement of either knuckle, dogs 24 are used, one on each head. Each dog is substantially L shaped and is pivoted through the free end of its longer arm and adapted to swing vertically upward on its 80 pivot. It is mounted in a small boxing or frame 25 secured to each head, in any suitable manner and on the side opposite to that carrying the coupling hooks and knuckle. Through this wall of the head is formed an 85 opening 100, opposite the opening for ear 7. It is adapted to receive the shoulder 6 and part of the hook of the coupling knuckle of the interlocking head, as shown in Fig. 6 and to allow the passage of dog 24 to engage such knuckle for uncoupling. To actuate each dog 24, a short lever 26 is used, fulcrumed on frame 25 and working in slots in the frame. Lever 26 is worked by the usual coupling pin lever, through a chain 90 or other suitable connection, as will be readily understood. Normally, the dogs 24 gravitate to inoperative position.

The coupling function of the coupling hooks 2 lies in their co-operation with the 100 knuckle 27 of the Janney type of coupling as shown in Fig. 9. It is not thought that further explanation of this feature is necessary, as it is evident from the drawings. Thus, it is equally possible to use one of 105 these couplings either with a Janney type or with another coupling of the same type.

Thus, the coupling hooks 2 have two distinct and separate functions: First, they act to guide two coupling heads accurately to 110 interlocking position, and, second, they co-operate with the knuckle of the Janney type of coupling.

In order to overcome any possible tendency toward twisting of the coupler heads, 115 relatively to one another, they are each provided with a lug 29 on one vertical front edge, at about the center, and a corresponding notch 28 at about the same point in the opposite edge, the notch of one head being 120 adapted to receive the lug of the other. Thus, when the two heads are once interlocked they become, practically, one solid piece which can not become separated by any possible accident short of complete destruction.

On the under face of each coupler head, just in advance of the pins 15, are carried a pair of guides 30. Preferably, they are cast integrally with the head and at one opera- 130

tion, but, of course, may be otherwise secured either removably or in fixed relation. Slidably and removably mounted in said guides are train pipe blocks 31 with flanges 32 supporting them on the guides. They are of such length that, when fully inserted, they abut against the projecting ends of pins 15 which act as stops for them. Each block is provided with one or more longitudinal bores or passages—for passenger cars, 10 three passages, and for freight, one. In each passage is a short pipe section 33 which extends a short distance beyond each end of the block. Each end of each pipe is threaded and on each threaded end is turned a nut 34. By loosening the nut on one end and tightening the nut on the other it is possible to adjust the pipe lengthwise through the block and, at the same time, secure it in 15 adjusted position, so that the pipe ends of the two blocks may be adjusted toward or from each other as required, to make a tight compression joint, as will later appear. In Fig. 5 hose ends and gaskets have been 20 omitted to more clearly show the adjustment. To the rear end of each pipe 33 is connected a train pipe 35, by means of an ordinary coupling sleeve 36, or the like. To the forward end of each is fastened, by a 25 clamp 37, a short length of hose or rubber tubing 38 carrying, inside, a gasket. The rubber tubing projects a short distance beyond the gasket. Thus, when the two heads 30 are driven tight together in interlocked or coupled position, the hose ends 38 of one are forced against the hose ends of the other block until the gaskets of one rest against the gaskets of the other. The projecting 35 rubber ends are forcibly compressed longitudinally and spread radially, as in Fig. 2, 40 making a very tight joint. This joint may be regulated by the adjustment of the pipe sections 33, as will be clear. Thus, all train pipes will be accurately and efficiently automatically coupled when the cars are coupled 45 by interlocking a pair of the heads 1. Since there is absolutely no relative movement between the coupled heads, the coupling of the train pipes is efficiently maintained as long 50 as the heads are coupled.

Assume that it is desired to couple a heavily loaded car to an empty on a very sharp curve. As the cars approach each other, the inclines 3 engaging the horizontal 55 edges of the top and bottom walls of the coupler heads, will bring the heads into the same horizontal plane, and the rounded ends of the same coupling hooks will engage the vertical wall of the chamber and swing them 60 into the same vertical plane. As they are forced together, the vertical edge of the chamber of each head will engage the rounded portion leading to the shoulder 6 of the coupling knuckle of the other head, forcing the knuckles to swing inwardly about their

pivots and compressing their springs 13. As the shoulders 6 reach the openings 100 the springs 13 will snap the knuckles outwardly so that shoulders 6 will engage the vertical walls of the openings, as shown in Fig. 6, this 70 gives a firm four point connection or coupling, firmly interlocked. At the same instant, the lugs 29 seat firmly in notches 28 and the compression coupling of the train pipes is completed. 75

It is thought that the construction, operation, and use of the invention will be clear from the preceding detailed description.

Changes may be made in the construction, arrangement, and disposition of the several 80 parts of the invention, within the scope of the appended claims, without in any way departing from the field and scope of the invention, and it is meant to include all such within this application wherein only a pre- 85 fered form has been disclosed.

Having thus fully described my invention what I claim and desire to protect by Letters Patent is:—

1. In combination, a pair of hollow coupling heads each provided with openings in its opposite side walls and a coupling knuckle provided with a coupling hook having a locking shoulder adapted to engage the wall of the opening in the other head, 95 each knuckle being also provided with a tripping toe adapted to be engaged by the hooked end of the other knuckle to effect uncoupling.

2. In a car coupler, a hollow coupler head 100 having an open front, a coupling knuckle pivoted to the head at one side of the longitudinal axis of the head and projecting forward so as to protrude from within the head, said knuckle having on the outer side of the 105 protruding portion an interlocking shoulder, and on the outer side of the portion within the head a projecting ear, an abutment on the head forward of the said ear relatively disposed so as to engage with said ear, and 110 an abutment within the hollow head on the side opposite the abutment that engages the said ear, which is adapted to interlock with an interlocking shoulder on the knuckle of a corresponding companion coupler. 115

3. In a car coupler, a hollow coupler head having an open front and a rear inner wall, a pivoted knuckle within said head at one side thereof, said knuckle having an end protruding forward from within said head, 120 an interlocking shoulder on its outer side, and a rearward portion extending transversely, said portion having a tripping toe on its end adapted to be engaged by the projecting end of a companion knuckle in its 125 uncoupling movement; and a resilient device bearing against said rear inner wall and the transversely extending rearward portion of the knuckle, and exerting its tension to force the protruding end of the knuckle outward 130

away from the longitudinal axis of the coupler.

4. In a car coupler, a hollow coupler head having an open front, mounted so as to swing laterally, a knuckle pivoted within said head at one side thereof, said knuckle having an end protruding forward from within said head, an interlocking shoulder on the outer side, a hooked extremity provided with a cam-like front, said hook opening toward the longitudinal axis of said head, and a transverse rearward portion on said knuckle extending substantially to said longitudinal axis and having a forward cam face adapted to coöperate with the cam-like front of said hooked extremity of a coöperating knuckle during the uncoupling movement of the latter; and an abutment in the wall of said head opposite said knuckle adapted to interlock with the shoulder of a knuckle on a corresponding mating coupler.

5. In a car coupler, a hollow coupler head having an open front, a pivoted knuckle carried by the head, said knuckle having an end protruding forward from within said head, an interlocking shoulder on the outer side of said protruding end, a hook on said knuckle opposite said shoulder, said hook having a cam-like front end, and said hook opening toward the longitudinal axis of the head, a transverse rearward portion on said knuckle extending substantially to the said longitudinal axis, the cam-like end of a coöperating coupling hook being adapted to engage the extremity of said transverse rearward hook on the other coupling during uncoupling movements of one of said knuckles; an abutment in the wall of the head opposite the knuckle adapted to interlock with the shoulder of a corresponding mating coupler, said parts being so disposed that when two heads are coupled, movement of one knuckle to disengage its interlocking shoulder from the abutment in the interlocked head will effect a disengagement of the companion knuckle.

6. In a car coupler, a hollow coupling head having an open front, a pivoted knuckle protruding forward of said head at one side of the longitudinal axis of said head, and having an interlocking shoulder on the outer side of the protruding portion; the side wall opposite the knuckle having an opening therethrough disposed in position to interlock with the interlocking shoulder in the knuckle of a corresponding coupler head, an angular dog pivoted on the outside of the wall adjacent said opening and having the

end of one arm arranged to bear upon the shoulder of the knuckle of a mating coupler 60 to release it.

7. In a car coupler, a hollow coupling head having an open front and having an opening through one side wall adapted to be engaged by an interlocking shoulder on the 65 knuckle of a companion coupler, a housing on the exterior of the wall, an angular dog having one end pivoted within the housing and its other end arranged to engage the said interlocking shoulder, a cam surface on 70 the back of the dog near its pivotal point, and a lever guided by the housing and adapted to bear upon said cam surface to move the angular dog to disengage said knuckle.

8. In a car coupler, a hollow coupler head having an open front end, a rigid hook projecting from the head forward of the front end at one side of the longitudinal axis of the head, the hook cavity facing the axis; a 80 pivoted knuckle projecting forward to substantially the same extent as the rigid hook, the projecting portions of said hook and knuckle being approximately similar in form and size, and being disposed in substantial registration; an interlocking shoulder on the outer side of the projecting portion of the knuckle, and the wall of the head that is opposite the hook and knuckle having an abutment adapted to engage the shoulder 90 on the knuckle of a corresponding coupler head.

9. In a car coupler, a hollow coupler head, an upper and a lower rigid hook of similar size and form protruding from said head 95 forward of the front thereof at one side of the longitudinal axis of the head, said hooks being spaced apart and having the hook cavities facing said axis; a knuckle pivoted in the space between said hooks within the 100 head, said knuckle projecting forward beyond the front of said head substantially the same extent as the hooks, said projecting portion of the knuckle being approximately 105 similar in outline and size to the projecting portions of the hooks; an interlocking shoulder on the outer side of the projecting portion of the knuckle; and the wall opposite the hooks and knuckle having an abutment adapted to be engaged by the interlocking 110 shoulder on the knuckle of a companion coupler head.

Signed at Ville St. Laurent, Montreal, Quebec, Canada, this 28th day of August, 1916.

ONESIME HEBERT.
